UNITED STATES PATENT OFFICE.

LEWIS S. BROWN, OF SAGINAW, MICHIGAN.

HOOK BUTTON.

Application filed April 3, 1922. Serial No. 549,075.

To all whom it may concern:

Be it known that I, LEWIS S. BROWN, a citizen of the United States, residing at Saginaw, in the county of Saginaw and 5 State of Michigan, have invented certain new and useful Improvements in Hook Buttons, of which the following is a specification, reference being had to the accompanying drawings.

10 This invention relates to certain improvements in hook buttons and it is an object of the invention to provide a novel improved device of this general character wherein the strain or pull imposed thereon 15 is not directly upon the threads attaching the button on a garment.

Another object of the invention is to provide a novel improved device of this general character which is adapted to be attached to the waist line of trousers or the like and which is provided with a means whereby a tab of a suspender may be readily and conveniently engaged therewith, said means also serving as a guide or holder 25 for a belt.

The invention consists in the details of construction and in the combination and arrangement of the several parts of my improved hook button whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:

Figure 1 is an elevational view illustrating a hook button constructed in accordance with an embodiment of my invention,

Figure 2 is an elevational view illustrating my improved hook button as herein disclosed in applied position,

Figure 3 is a view in rear elevation of the structure as illustrated in Figure 2, and

Figure 4 is a view in edge elevation of my improved hook button in applied position.

As disclosed in the accompanying drawings 1 denotes the body portion of my improved hook button formed of metal or

other desired material and which is herein disclosed as circular in form. The marginal portion of the body 1 is provided with the openings 2 to provide means whereby the device may be effectively sewed in applied position on a garment or the like.

55 Integrally connected with the edge of the body 1 is an arm 3 having its outer portion 3^a returned to overlie the body 1 but spaced therefrom, said returned portion 3^a being of such length to extend beyond the side of the body 1 remote from the arm 3.

60 The free extremity of the portion 3^a is outwardly curved as at b to facilitate the entrance thereof. My improved hook button is particularly adapted for use in connection with the waist line of trousers and in applying the same the body 1 overlies the inner face of the garment at the waist line and is sewed thereto, the stitches being disposed through the openings 2. The returned portion 3^a of the arm overlies the 65 outer face of the garment at the waist line and is disposed downwardly. A tab of a suspender may be readily engaged with the

70 arm 3 in a manner to effect the desired support of the trousers and in a manner whereby the tab does not have direct contact with the connecting threads with the result of the liability of the device becoming displaced is materially reduced. The arm 3 or more particularly the returned portion 75 3^a thereof also provides a guide or open loop to receive a belt and which arrangement can be employed with the same advantage as the well known fabric loops now employed.

80 From the foregoing description it is 85 thought to be obvious that a hook button constructed in accordance with my invention is particularly well adapted for use by reason of the convenience and facility with which it may be assembled and operated, 90 and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

100 I claim:

105 As a new article of manufacture, a hook

button comprising a circular body having its marginal portion provided with an annular series of openings, an arm formed with the body extending outwardly and 5 radially therefrom, said arm being continued by a returned portion overlying the body and spaced therefrom, said returned

portion being of a length to extend beyond the side portion of the body remote from the arm, said extension being disposed outwardly. 10

In testimony whereof I hereunto affix my signature.

LEWIS S. BROWN.
